Joshua R. Ingalls

UNITED STATES PATENT OFFICE.

JOSHUA K. INGALLS, OF WILLIAMSBURG, NEW YORK.

CATCH FOR VAULT-COVERS.

Specification of Letters Patent No. 11,227, dated July 4, 1854.

To all whom it may concern:

Be it known that I, JOSHUA K. INGALLS, of the city of Williamsburg, county of Kings, and State of New York, have invented a new and useful improvement in locks or fastenings for vault-covers, so arranged that by pulling a cord on the inside of the vault the cover becomes unlocked and may be removed, but by replacing the cover

10 the lock is so operated that it fastens the cover down without further aid.

My improvement is also applicable to the fastening of hatches, trap doors, &c.

To enable those skilled in the art to make 15 and use my invention, I will proceed to describe its construction and operation, reference being had to the annexed drawings, forming a part of this specification, in which—

20 Figures 1 and 2 are side sectional views of my improvements.

Similar letters refer to like parts.

25 *a*, represents the pavement; *b*, vault cover; *c*, *e*, ears; *d*, hanger; *d'*, bearing; *f*, weighted lever cam; *g*, cord; 1, 2, cams; 3, lever; 4, weight; 5, cavity.

In large cities, where vaults are in general use beneath the street in front of dwellings and other buildings, the occurrence of serious 30 accidents from the want of some adequate means of fastening down the vault covers is quite frequent. The vaults are generally arranged with openings in the top for the admission of coal and wood or other articles. These openings generally occur in the center or sides of the pavement, and are continually traveled over by foot passengers. When a vault cover is not properly fastened 35 it is liable to slip, if an unfortunate passenger treads upon it, and his leg goes through into the opening; the result is a broken limb or other injury. Robberies are also frequent, the thieves gaining entrance through the vault holes.

40 By my improvement vault covers may be fastened down in the most effectual manner and with great convenience. The pavement immediately surrounding the vault opening is composed of stone or iron (*a*) into which 45 the cover (*b*) fits. The cover (*b*) has two

ears (*c* and *e*). The ear (*e*) is curved so as to pass under the edge of *a*, and thus secure that side of the cover. The ear (*c*) is perforated so that the nose of cam (1) may pass through and fasten down the cover as seen 55 in Fig. 1; or the ear (*c*) may be made a little curved or notched like *e*, so that the nose of the cam (1) may touch on the notch and thus hold the cover fast.

Fig. 1, shows the cover locked down. Fig. 60 2, shows the cover unlocked ready to be removed.

The weighted lever cam (*f*) has a bearing at *d'* by means of the hanger *d*, in the manner shown. The weight (4) serves to pull 65 down the weighted lever cam, so that the nose of cam 1, enters the ear *c*, and the cover is fastened down in the manner shown in Fig. 1.

When it is desired to unlock the cover 70 (Fig. 2,) the cord *g* is pulled, which operating on the lever (3), the weighted lever cam (*f*) turns upon its bearing (*d'*) whereby the nose of cam 1, is withdrawn from the ear (*c*) which latter immediately touches on 75 the upper part of cam 2 until it passes the nose of cam 2, when the ear (*d*) drops into the cavity (5) and holds up the weighted lever cam (*f*) in the manner shown in Fig. 2. The cover (*b*) being now unlocked may 80 be removed but no sooner is the ear *d* lifted than the weighted lever cam (*f*) previously held up by the catch at 2 having now no support returns to its original position shown in Fig. 1. If it is now desired to return the cover to its place the side bearing upon its ear (*e*) is first put down so that the ear *e* shall catch under the edge of *a*. On bringing down the other side having 85 upon it ear (*c*) the latter presses upon the upper part cam 1, and throws back the weighted lever cam *f*, until the ear (*d*) passes the nose of cam 1, whereupon the weighted lever cam (*f*) returns to its position and the nose of cam 1 catches in the 90 ear *d*; thus the cover becomes locked as seen in Fig. 1.

The use of the weight (4) is simply to bring back the lever cam (*f*) after having been pulled up by the cord (*g*). It is mani- 100

fest a spring may be used to operate the lever cam (f) in place of the weight (4) if desired.

Having thus described my invention, what I claim as my invention and desire to secure by Letters Patent, is—

The additional lip or nose 2, with the recess 5, for the eye of the cover to fit into,

and hold the catch, unlocked, as arranged in relation to the other parts of the catch 10 or lock, and operated as herein set forth.

JOSHUA K. INGALLS.
